DenmarkApplication May 18, 1935, Serial No. 22,254
In Denmark May 23, 1934

3 Claims. (Cl. 46—68)

It is feasible, in known manner, to transmit kinetic energy to rotating whirligigs—so-called blow-tops—and it is similarly known to construct so-called leaping tops which, after having received a sufficient kinetic energy in the shape of rotation, are able to perform a greater or smaller number of leaps with decreasing heights, until the leaping energy or rotation energy has been consumed.

On the other hand, it is not known to construct a leaping blow-top by combining a leaping device and blowing device in one and the same top, or to use this combination for rotary balls or soaring bodies.

By such a combination the rotation can be maintained for an unlimited period, while at the same time the body concerned may be caused to perform leaps, from the implement belonging to the game, down on to some base or other, and up again on to the implement, when the body concerned is a whirligig, or to let the body perform soaring trips, when the body concerned is a ball or a soaring body.

A couple of constructions of the invention are illustrated on the drawing,

Fig. 1 showing the invention applied to a top, partly in section, partly in side elevation,

Fig. 2 the same applied to a soaring body, also partly in section,

Fig. 3 a spindle with button and pin from Figs. 1 and 2.

In Figs. 1 and 2, the transmission of energy is effected by a blow on the button 1, and friction must be present between the button and the body supplying the blow. The energy is transmitted by way of the spindle 2 to the pin 3, at which point the energy is transmitted to the threads 4, which by means of the pipe R are firmly connected to the masses M or L, the rotation of which is to be increased. In order that 1, 2, 3 may return to the initial position, 2 rests with its point in a recess in the body 5, which is supported by a compressed spring 6. Fig. 1 shows a leaping device 7 consisting of a spring, a rubber body or some other resilient device, whereas Fig. 2 is fitted with two exactly similar blow-

devices adapted each to act either as a blow-device or as a leaping device.

The whirligig, as shown in Fig. 1, can perform leaps in that its point strikes a floor or some other surface, whereas the soaring body, as shown in Fig. 2, after having attained a suitable velocity, can be used as a kind of ball, which subsequently may receive its impulses partly by blows from below, partly by blows from above, after the velocity has been reduced.

It is necessary to provide a sufficient friction between the blowing implement and the friction button 1, and to give the blow a sufficient duration, which is attained by providing a sufficient elasticity in the blowing implement, the rotating body or the support.

As mentioned above, there are various manners in which the blow-device as well as the leap-device may be constructed, and the manners indicated here are merely chosen at random.

Having thus described my invention, what I claim is:

1. A whirligig comprising a body, cam means carried by said body at opposite sides thereof whereby a rotational impulse may be transmitted to said body, means coacting with said cam means mounted slidably in said body and yielding means mounted in said body normally urging said coacting means outwardly from said body so that a blow upon said coacting means will rotate said body.

2. A whirligig comprising a body, nut devices located on opposite sides of said body, elastic screwing means extending on opposite sides of said body and engaging said nut devices whereby blows upon said screwing means will cause the whirligig to spin, leap and fly.

3. A whirligig comprising a body, a nut device cooperating with said body, elastic means extending at one side of said body and engaging said nut device, elastic means extending at the opposite side of said body whereby blows upon said elastic means engaging said nut device will cause the whirligig to spin, leap and fly.

FREDERIK VILHELM BELSTRUP.
